UNITED STATES PATENT OFFICE

STANLEY A. JACQUES, OF CHICAGO, ILLINOIS, ASSIGNOR TO INTERNATIONAL COMBUSTION ENGINEERING CORPORATION, OF NEW YORK, N. Y., A CORPORATION OF NEW YORK

PULVERIZED COAL DISTRIBUTOR

Application filed January 29, 1926. Serial No. 84,747.

This invention relates to distributors such as are used to distribute materials in a state of division, such, for example, as pulverized coal, in connection with which the invention 5 is particularly useful.

One of the objects of the invention is to provide an improved means whereby a stream of such material as pulverized coal may be uniformly and effectively distributed between 10 several branches. As illustrative of this object it is customary, in the burning of pulverized coal, to employ a plurality of burners, the coal being supplied to said burners through pipes branching from a main conduit 15 or supply line. Uniformity of feed and relative equality of distribution is highly desirable, and this is accomplished by means of my invention.

More specifically it is an object of my invention to provide a distributor which is of 20 simple construction and easy and inexpensive to manufacture.

The foregoing, together with such other objects as may hereinafter appear, or are incident to my invention, are realized by a construction which I have illustrated in the preferred form in the accompanying drawings, wherein—

Fig. 1 is a section taken through my distributor mechanism on the line 1—1 of Fig. 2.

Fig. 2 is a partial section and side elevation of Fig. 1, the section being taken on the line 2—2 of Fig. 1.

Fig. 3 is a perspective view showing a number of the distributing elements employed in carrying out my invention.

Referring now to Figs. 1 and 2, the reference character 7 denotes a tubular coupling member or throat adapted to be connected to the main supply conduit not shown. Attached to the member 7 is a Y or other forked member 8, the legs 9 of which are adapted to be connected to the branch pipes (not shown) leading to the burners or other points, as the case may be. At each of two opposite sides the upper portion of the member 8 has inwardly projecting lips or ribs 10 from which the distributor elements 11 are suspended. These distributor elements 11 are counterparts of one another. They are triangular-

shaped, and comprise a side wall portion 12 and an end wall portion 13 having at its upper edge a shoulder 14 adapted to rest upon one of the ribs 10. At the opposite upper corner there is a spacer lug 15 projecting from the side wall 12 and serving as a means for suspending the distributor element from the other rib 10 of the member 8. When the elements are assembled in alternately reversed relation, they cooperate to provide oppositely inclined chutes or channels alternately directing coal to the branches 9 of the member 8. The effect of the distributors is to split up the main stream of coal into a plurality of smaller streams, and certain of these smaller streams are directed into one branch 9 and the remainder into the other branch 9. The smaller streams delivered to each branch reunite into a single stream. This produces what may be termed a reconditioning of the coal, in which connection it is to be understood that the coal is transported through the medium of the air, i. e., the material delivered to the distributor is a mixture of coal and air. This reconditioning produces a uniform state 70 of the mixture of coal, and air in the branches, and the construction and disposition of the distributor elements secures an approximate 75 uniform distribution as between the branches. While I have shown the distributor as comprising six distributor elements, the number thereof may be increased or decreased by relatively decreasing or increasing the size of the elements to secure greater or less degree of uniformity and equality of 80 distribution as the nature of the particular material and the needs of the particular service may demand.

What I claim is:—

1. A distributor mechanism for pulverized coal and the like comprising a branched conduit and a plurality of counterpart distributor elements, each with a single inclined directing flange, hung therein alternately in reversed relation to provide alternately inclined chutes.

2. A distributor mechanism for pulverized coal and the like comprising a branched conduit and a plurality of distributor elements therein in advance of the branches each com-

prising a side wall and a single inclined end wall with means for suspending the elements from their upper corners.

3. In distributor mechanism for pulverized coal and the like, a reversible distributor element comprising a triangular plate adapted to act as a vertical division wall and having a single laterally projecting portion at an edge thereof adapted to act as a deflecting or guiding member.

4. In distributor mechanism for pulverized coal or the like, a distributor element, shiftable in position, comprising a triangular plate adapted to act as a vertical division wall, and having a laterally projecting portion at an edge thereof adapted to act as a deflecting or guiding member, together with suspension means at the three corners of the element so arranged that two of them will support it in whatever position it is set.

5. In distributor mechanism for pulverized coal or the like, a distributor element, shiftable in position, comprising a triangular plate adapted to act as a vertical division wall, and having a laterally projecting portion at an edge thereof adapted to act as a deflecting or guiding member, together with suspension means at the three corners of the element, at least one of which serves also as a spacer between the element and a like adjacent element.

6. In distributor mechanism for pulverized coal and the like, a distributor element comprising a triangular plate adapted to act as a vertical division wall and having a laterally projecting portion at an edge thereof adapted to act as a deflecting or guiding member, said element having seating means at the top whereby it may be rigidly suspended.

7. A distributor mechanism for pulverized coal and the like, comprising a branched conduit, and a plurality of spaced division plates in advance of the branches, each plate having a laterally extending inclined guiding or deflecting portion and being equilaterally triangular in shape so that it may be shifted in position by rotation in its own plane to cause the laterally extending portion thereof to deflect either to one side or the other.

In testimony whereof I have hereunto signed my name.

STANLEY A. JACQUES.
